(57) **CLAIM**

The ornamental design for a hosiery donning device, as shown and described.

DESCRIPTION

FIG. 1 is a front elevation view of a hosiery donning device;
FIG. 2 is a rear elevation view thereof;
FIG. 3 is a left side elevation view thereof;
FIG. 4 is a right side elevation view thereof; and,
FIG. 5 is a perspective view thereof.

The broken line showing of features of the article of manufacture is for the purpose of illustrating environmental structure and forms no part of the claimed design.

1 Claim, 3 Drawing Sheets**FIG. 3**

FIG. 4

FIG. 5
